UNITED STATES PATENT OFFICE.

MARC GRANDJEAN, OF PARIS, FRANCE.

PAPER HOLDER FOR STENOGRAPHIC AND LIKE MACHINES.

Application filed December 22, 1921. Serial No. 524,184.

To all whom it may concern:

Be it known that I, MARC GRANDJEAN, a citizen of the Republic of France, and residing at Paris, Seine Department, Bourse du Commerce, Rue du Louvre, in the Republic of France, have invented certain new and useful Paper Holders for Stenographic and like Machines, of which the following is a specification.

10 My invention relates to a removable and pivoted paper holder which is applicable to stenographic and like machines printing upon a continuous paper band. The said holder comprises a frame carrying the winding reel, the top of the said frame constituting a shelf or desk which may be used if required for making corrections or annotations upon the band. The said frame is of rigid construction and rests upon pivots disposed on opposite sides in such manner that it is enabled to support the pressure of the band in making corrections without sinking or bending. The frame is cut out at one side in order to permit the paper to be rolled up by the reel and to be removed by a sliding action.

The accompanying drawing given by way of example shows an embodiment of the invention.

30 Fig. 1 is a vertical section of the device. Fig. 2 is a plan view of the same. The holder comprises a frame 1 having disposed at one end thereof two pivots 2 journaled in the frame of the machine. The said frame consists of a shelf or table whereof the inner end 1^a is rounded, and two side portions or cheeks 1^b, 1^c, having secured thereto the pivots 2. The side portion 1 does not extend beyond the shelf, whilst the side portion 1^c is extended beyond the forward edge 1^d in order to support the reel 3 for holding the printed paper 4. Inasmuch as the sides are cross-braced by the shelf or table, the frame 1 may be given all the necessary strength. It is also supported at both sides by the pivots 2 and is thus well held in the straight position and is enabled to support a considerable strain without bending or sinking.

The strip of printed paper 4 is moved to 50 the front part of the said table, travels over the same and is rolled up at 3. The said table forms a desk for making corrections and annotations by hand upon the paper band. At the end of the side portion 1^c is 55 secured a shaft having revoluble thereon the reel 3. After travelling above the said desk, the paper may be rolled up by the use of a milled button or by a device connecting the reel with the machine having the said holder 60 secured thereto. The device for the automatic winding of the paper may be varied according to the arrangement of the machine.

The frame 1 is cut out in order to provide 65 for the winding of the printed paper without making it necessary to remove the reel nor to unwind the paper. When the machine is not in use, it will suffice to fold back the said holder upon the machine by pivoting the same upon the pivots 2. When in use the holder is clamped at the desired inclination by suitable fastening means appropriate to the machine whereupon the said holder is used. 75

Claim:

A paper holder for stenographic and like machines, comprising a frame constituted by two lateral cheeks whereof one is longer than the other, an axle disposed in the overhang position upon the longer of the said cheeks, a reel revoluble upon the said axle and serving to receive the paper band, a table top connecting the two cheeks and disposed forwardly of the said reel, the said top serving as a desk for making hand corrections upon the paper band, and an axle mounted on each of the said cheeks whereupon the paper holder may be pivoted. 80 85

In testimony that I claim the foregoing 90 as my invention, I have signed my name in presence of a subscribing witness.

MARC GRANDJEAN.

Witness:

MAURICE ROUX.
